MAURICE A. RICHFORD, OF OAKLAND, CALIFORNIA

BURNER TIP

Application filed April 14, 1930. Serial No. 444,102.

This invention relates to gas burners of the Bunsen type and especially to an auxiliary burner tip whereby the main flame of the Bunsen burner is maintained.

Atmospheric pressure burners of the Bunsen type such as used in laboratories and like places usually consist of a burner tube, a gas nozzle or tip whereby a mixture of gas and air is directed into the burner tube and a base member supporting the tip and the tube. The nozzle or tip directs a jet of gas into one end of the burner tube and the jet action of the gas causes an induction of a sufficient amount of air to produce a mixture of gas and air which burns with a blue flame from the opposite end of the burner tube.

Atmospheric burners of the Bunsen type operate very satisfactorily where so-called artificial or manufactured gas is used; that is, a gas having a comparatively low B. t. u. content, usually 400 to 600 B. t. u.'s per cubic foot. The different kinds of flames, namely, reducing and oxidizing, are easily secured with this type of burner when using manufactured gas. However, when a gas having a high B. t. u. content is encountered, and especially natural gas with a content of about 1100 B. t. u. per cubic foot, trouble is experienced in keeping the flame lighted. When burning the gas in a sharp or oxidizing condition, the flame has a marked tendency to blow out at the slightest disturbances, such as drafts and movements. The reason for this is that natural gases do not contain free hydrogen, a rapid burning gas which imparts to manufactured gas a high rate of flame propagation. On the contrary, natural gas contains a large percentage of methane, the slowest burning of the commercial gases.

The additional air required to yield a sharp flame with natural gas increases the speed of the gas and air mixture equal to or exceeding that of the velocity of the flame propagation. The flame then becomes unstable and extinguishes or "blows out" very easily. In fact, an oxidizing flame with a moderately well defined inner cone often cannot be kept lighted even momentarily.

The object of the present invention is to generally improve and simplify the construc-

tion and operation of burners of the character described and particularly to provide a burner which is capable of handling natural gas without any danger of the flame becoming extinguished; to provide an auxiliary burner tip which is adapted to be applied to burner tubes such as employed in laboratory burners and the like and which is adapted to be applied in such a position as to supply a small auxiliary or pilot flame whereby combustion or burning of the main flame is insured; and further, to provide means whereby a small portion of the gas and air mixture passing through the main burner tube is directed to the auxiliary burner tip and the flow of gas therethrough maintained at low velocity.

The invention is shown by way of illustration in the accompanying drawing, in which:

Fig. 1 is a side elevation of a Bunsen burner, showing the application of the auxiliary burner tip; and

Fig. 2 is a plan view of the main tube and the auxiliary burner tip applied thereto.

Referring to the drawing in detail, and especially Fig. 1, A indicates a base member of suitable construction, 2 a main burner tube, 3 a yoke whereby the burner tube is secured and supported with relation to the base, 4 a thumb screw engageable with the main burner tube to secure it and to permit vertical adjustment. 5 indicates a tube on the base which is adapted to be connected with a source of gas supply, and 6 a nozzle or gas tip whereby gas is directed into the lower end of the main burner tube indicated at 2. The structure so far described is more or less common and illustrates Bunsen burners of the laboratory type. The invention forming the subject matter of the present application is the auxiliary burner tip indicated at 1. The tip is nothing more or less than a short sleeve which is frictionally or otherwise secured on the upper end of the main burner tube, the upper inner end of the sleeve is turned out to form an annular surrounding chamber such as shown at 7, and this chamber is supplied with a mixture of air and gas through perforations 8 formed in the main burner tube. These perforations are preferably

formed by punching the tube so as to form the series of lugs or baffle members 9 which are bent inwardly so as to intercept the upwardly moving stream of gas and air and so as to divert a portion thereof into the annular chamber 7.

In actual practice the burner is particularly designed for natural gas. The gas discharging through the nozzle 6 is directed upwardly into the lower end of the main burner tube and by its jet action induces a sufficient amount of air to form a mixture of gas and air which burns with a blue flame from the upper end of the tube. Natural gas contains a large proportion of methane gas, and this is rather difficult to burn in atmospheric pressure burners of the type here illustrated. It will, however, readily burn if supported by an auxiliary flame. In the present instance a mixture of gas and air under a relatively high velocity discharges from the upper end of the tube and will under ordinary circumstances not burn as the flame leaves the upper end of the tube. In the present instance a small portion of the mixture is diverted by the inwardly extending baffle members 9 and directed through the perforations 8 into the annular chamber 7. The mixture thus diverted discharges at low velocity through the upper end of the annular chamber and there unites with the main flame and insures continuous burning thereof. The pilot light or flame is ring-shaped, due to the formation of the annular chamber; and due to the low velocity of the gas passing therethrough the flame will stick tightly to the tip and thus give continuous ignition to the fast moving gas and air mixture leaving the main burner tube.

While certain features of the present invention are more or less specifically described, I wish it understood that various changes may be resorted to within the scope of the appended claims. Similarly, that the materials and finishes of the several parts employed may be such as the manufacturer may decide, or varying conditions or uses may demand.

Having thus described my invention, what I claim and desire to secure by Letters Patent is—

1. In a burner of the character described, an elongated main burner tube, means adjacent one end of the tube for supplying a mixture of gas and air, a sleeve secured to the opposite end of the tube and forming an annular chamber exterior to the main tube, said main tube having perforations formed therein in communication with the annular chamber, and a plurality of baffle members interior of the main tube whereby a small portion of the gas and air mixture discharging therethrough is diverted through the perforations into the annular chamber.

2. In a burner of the character described,

a main elongated burner tube of substantially uniform diameter throughout its length and having an unobstructed inlet and outlet at opposite ends, a sleeve secured exterior of the tube adjacent the outlet end and forming an annular chamber open at one end, means adjacent the inlet end of the tube for supplying air and gas to be mixed during passage through the tube and to form a high velocity main flame, and means for diverting a small portion of said mixture from the main tube into the annular chamber to cause a low velocity flow of gas through the annular chamber to form a low velocity pilot flame.
